LAMP BASE HOLDER FOR AUTOMATIC
BASE FILLING MACHINES

Thomas G. Shaffer, Fairmont, W. Va., assignor
to Westinghouse Electric Corporation, East
Pittsburgh, Pa., a corporation of Pennsylvania

Application December 28, 1951, Serial No. 263,940

1 Claim. (Cl. 118—3)

1

This invention relates to base filling machines and, more particularly, to a base holder therefor. The bases for incandescent lamps provide the means of connecting the lamp bulb to the socket. For general lighting purposes, screw type bases are most commonly employed. Most screw type bases are attached to the bulb by means of a basing cement especially designed for the purpose. The bases are filled with cement prior to basing on an automatic base filling machine having a plurality of, such as, for example, 12 heads or stations. The bases are held in holders in the heads which rotate on the machine frame and index from station to station. They are automatically filled with cement from a reservoir or distributor in the cement filling station of the machine.

The conventional base holders are usually octagonal shaped strips or springs of tempered bronze located in a hollow base nest in each individual head. These holders are unsatisfactory in that they permit the base to slip in the head during rotation, thereby producing an uneven filling or deposition of cement around the interior periphery of the base.

As a solution to the problem, I first thought that a rubber ring in the hollow base nest should be employed. Although the ring kept the base from slipping, it did not prevent wobble or sideways motion during rotation. Uneven base filling often resulted. Next a cup-shaped holder having prongs or fingers for gripping the base and a surrounding sleeve in the base nest were employed. The holder and sleeve held the base securely during initial use but after continued service, the prongs of the holder tended to spread, thus permitting the base to slip during rotation and filling.

Hence it was found advantageous, according to my invention, to place the rubber ring between the holder and the sleeve to produce a constant pressure on the base, thereby preventing slipping of the base during rotation and filling, and producing an even deposition of cement on the interior periphery of the base in the filling station.

In its general aspect, the present invention has as its object the elimination of the disadvantages and defects of the prior art base holders for an automatic base filling machine.

A specific object of the invention is a base holder assembly for an automatic base filling machine which prevents slipping of the base during rotation and filling.

Another object of the invention is a base holder

2

for an automatic base filling machine which produces an even filling of the base.

A further object is a base holder assembly for an automatic base filling machine having a rubber ring between a base holder and a retaining sleeve to produce a constant pressure on the base during rotation and filling thereof.

Other objects of the invention will appear to those skilled in the art to which it appertains as 10 the description thereof proceeds, both by direct recitation thereof and by implication from the context.

Referring to the accompanying drawing, in which like numerals of reference indicate similar 15 parts throughout the several views:

Fig. 1 is a side elevational view, partially in axial section, of a head of a base filling machine in the unloaded condition in a rotating station and showing the base holder assembly of my invention;

Fig. 2 is a plan view of the head with parts in section on the line II—II of Fig. 1, in the direction of the arrows;

Fig. 3 is a fragmentary axial sectional view of 25 the base holder assembly in the unloaded condition;

Fig. 4 is a view corresponding to Fig. 1, but showing the head in the loaded condition;

Fig. 5 is a fragmentary sectional view, similar 30 to Fig. 3, of the base holder assembly of my invention in the loaded condition;

Fig. 6 is a side elevational view, partially in section, of the head and cement reservoir at the cement filling station of the base filling machine.

Fig. 7 is a perspective view of the base holder 35 of my invention;

Fig. 8 is a side elevational view similar to Fig. 4, partially in section, of the head at the unloading non-rotating station; and

Fig. 9 is a diagrammatic plan view of a conventional base filling machine.

In the drawing, particularly in Fig. 6, a base holder head 10 of a multi-head automatic base filling machine 12 is shown beneath a cement reservoir and distributor 14 at a cement filling station of said machine. This head 10 has a hollow body 16 of cylindrical form rotatable in a bushing 18 in a table 20 of the machine 12.

Base holder head

The body 16 has a flanged annular upper portion or shoulder 22 which overlaps the upper surface of the bushing 18 and the table 20, and a lower portion 24 of reduced diameter. On the lower extremity of portion 24, a driven spur gear

26 is secured over a bottom cover plate 28, as by a bolt 30. Gear 26 is engaged by a driver spur gear 31, which in turn is rotated by driving means, such as a motor, not shown. This plate 28 underlies bushing 18 and the adjacent portion of the table 20. Vertical motion of the body 16 with respect to table 20 is prevented by the shoulder 22 of body 16 and the bottom plate 28.

An axial cavity 32 extends the length of the body 16. This cavity comprises a cylindrical base nest 34 in the upper portion of body 16, a middle clearance hole 36 of reduced cross section, and a base elevating shaft hole 38 of further reduced diameter in the lower portion of body 16. The inner surface of body 16 which forms the bottom side wall of clearance hole 36 is tapered upwardly from the vertical sides of said hole and forms an annular horizontal shoulder 40 at the upper end of the shaft hole 38.

A base elevating or ejecting shaft 42 is vertically slidable within shaft hole 38 on a cylindrical lower portion 44. This shaft 42 also comprises an annular middle portion or collar 46 above lower portion 44 for engagement with the shoulder 40 within body 16, and an upper portion 48 similar to bottom portion 44 but of reduced diameter for supporting a screw type base 49. In all stations of the machine 12, except the loading and unloading stations, the lower end of the shaft 38, as shown in Figs. 1, 4 and 6, is not in engagement with a cam track 50. However, in the unloading and loading stations, as shown in Fig. 8, engagement of the lower end of shaft 38 with a raised portion 51 of the cam track 50, as the machine 12 indexes into that station, elevates the shaft 38 and partially ejects a cement filled base 49 therefrom.

Within base nest 34 is provided a base holder assembly 52 of my invention. This assembly comprises a cup-like base holder 54 (Fig. 7) and a hollow cylindrical retaining member or sleeve 56 (Fig. 6) with an annular member or ring 58, suitably rubber, between said holder and said sleeve. As shown particularly in Fig. 7, holder 54 has a flanged lower portion 60 and a cup-like upper portion 62 having a nearly cylindrical and axially curved inner surface. The diameter at the open end of cup-like portion 62 is suitably slightly less than the base 49 and the same as base 49 at its bottom end. This upper portion 62 has a plurality of equi-spaced radial pie-shaped vertical slots 64 cut therethrough to form a plurality, six in the present showing, of flexible prongs or resilient fingers 66 having an L-shaped vertical cross section and designed to fit the contours of the base 49. The sleeve 56 has a lower inner annular projection 68 for supporting the ring 58.

A circular top cover plate 70, having an axial center hole to permit the insertion of the base 49 therethrough into the holder 54, is attached to the top surface of the body 16, as by three screws 72, shown in Fig. 2. This plate secures the holder 54 and the sleeve 56 in the base nest 34.

Cement reservoir

The cement reservoir and distributor 14, shown in Fig. 6, comprises a hollow reservoir 74 filled with a suitable cement 75, a hollow cylindrical plunger 76 threaded into the lower end of said reservoir and to which is fixed an upper guide bracket 78. A lower guide bracket 80 fixed to the frame of the machine (not shown) is provided to guide said plunger 76. A cap 81 is threaded into the lower end of said plunger. A guide sleeve

82 is disposed about the lower end of the plunger 76 and secured to the lower extremities of a pair of vertical guide rods 84 and 86. The lower end of the plunger 76 is of slightly reduced cross section and provided with a sleeve or bushing 88 thereabout to facilitate the vertically reciprocating motion of the plunger within the sleeve 82. A cement delivery aperture is provided through the bottom side wall of the plunger 76 and the sleeve 88 above the cap 81. The guide sleeve 82 has an annular top flange secured, as by bolts, to the lower reduced-section portions of the guide rods 84 and 86 by riveting over the lower ends thereof, as illustrated. The bottom face of sleeve 82 is tapered downwardly and has an annular portion 94 of reduced section at its lower end which fits into the opening of a base 49.

The lower guide bracket 80 which is slidable on the guide rods 84 and 86 has a pair of circular grooves 96 and 98 cut into its bottom face axial to and of larger diameter than said rods. About rods 84 and 86, recovery springs 100 and 102 extend from sleeve 82 into the grooves 96 and 98 respectively. Above lower guide bracket 80, the upper guide bracket 78 is also slidable on rods 84 and 86. On the upper end of rods 84 and 86 are provided pins 104 and 106, respectively, which project through suitable holes therein and limit the upper travel of the plunger 76.

Base filling machine and operation thereof

The automatic base filling machine 12 (Fig. 9) may comprise, for example, 12 of the heads 10 which are indexed from station to station automatically by conventional indexing means, not shown. The raised portion 51 (Fig. 8) of the cam track 50 may extend peripherally beneath the non-rotating unloading stations 9 through 12 and the non-rotating loading stations 1 through 3. Hence, particularly in the first unloading station 9, the base elevating shaft 42 is in its position of greatest vertical travel and, as shown in Fig. 8, has partially ejected the base 49 upwardly from the prongs 66 of the holder 54, so that an operator may remove the cement filled base 49 easily by hand. At stations 4 and 5, the shaft 42 leaves the raised portion 51 of the cam track 50 and drops down so that the annular collar 46 of shaft 42 rests on the shoulder 40 of the internal portions of the body 16.

At station 6, a conventional base inserting plunger (not shown) may be carried on plunger 76 of cement reservoir and distributor 14. This base inserting plunger pushes the base 49 downwardly between the fingers 66 of the holder 54 until the bottom of the base 49 rests on the top of the shaft 42.

At station 7, driver gear 31 rotates the driven gear 26 and hence the head 12 containing the base 49. Simultaneously, the reservoir 74 and the plunger 76 are moved downwardly by reciprocating means, such as a compressed air cylinder (not shown). The downward motion of the reservoir and plunger permit the guide sleeve 82 (Fig. 6) to slide downwardly until the lower tapered edge of the sleeve 82 contacts the open end of the base 49. Plunger 76 continues its downward travel sliding in sleeve 82 until the cement delivery aperture 90 projects below the bottom edge of the sleeve 82 and the cement 75 is distributed evenly therefrom to the inner periphery of the rotating base 49, as shown in Fig. 6. At the same time, the compression of the springs 100 and 102 on the guide rods 84 and

86 against the top of guide sleeve 32 maintains sleeve 82 in contact with the rotating base 49 during the filling operation.

At the end of the cement filling operation, plunger 76 is retracted upwardly, thereby withdrawing the aperture 90 from sleeve 82 and cleanly cutting off the flow of cement 75 from the base 49. When the upper guide bracket 78 strikes the pins 104 and 106, sleeve 82 is retracted with the plunger 76, upwardly from the base 49, thus permitting the indexing of the head 10 to the non-rotating station 8.

Holder operation

According to my invention, when the base 49 is pushed downwardly at station 7 by the base inserting plunger, the prongs 66 of holder 54 move outwardly from the axis of the holder 54 and the rubber ring 58 is readily compressed against the retaining sleeve 56. This permits the downward travel of the base 49 therein until said base rests on the shaft 42. The compressed rubber ring 58 cooperating with the resiliency of the fingers 66 produces a constant pressure on the base 49, thereby preventing slipping of said base during rotation in the filling station 7 and permitting the even deposition of cement 75 on the inner periphery of the base 49.

At station 9 the shaft 42 is elevated by the raised portion 51 of the cam track 50, and pushes upwardly on and partially ejects the base 49, allowing the prongs 66 of the holder 54 to again move inwardly toward the axis of the holder 54 and again relax the rubber ring 58.

Thus, it will be seen from the foregoing description that the base holder assembly 52 of my invention has eliminated the disadvantages and defects of the prior art base holders for automatic base filling machines. My base holder assembly 52 prevents slipping of the base 49 during rotation in the filling station 7 of said machine and permits the even filling or deposition of the cement 75 through aperture 90 in the lower end of plunger 76 of the cement reservoir and distributor 14 on to the inner periphery of the base 49. My base holder assembly 52 com-

prises a flanged cup-like holder 54 and a cylindrical retaining sleeve 56 with a rubber ring 58 therebetween and maintains a constant pressure on the base 49 through rotation and filling thereof.

Although a preferred embodiment of my base holder assembly has been described, it will be understood that modifications may be made within the spirit and scope of the appended claim.

I claim:

A cement filling station for an automatic base filling machine comprising a vertically reciprocable cement distributor, said distributor comprising a reservoir, a hollow vertical reciprocable plunger fixed to said reservoir and having a guide bracket on its upper end and a cap in its lower end, a guide sleeve having a tapered reduced lower end portion adapted to fit into the opening of a base, said plunger being reciprocable in the guide sleeve and provided with a cement delivery aperture cooperable with said guide sleeve as a valve, mounting rods fixed to said guide sleeve for guiding said guide bracket, means about said rods for biasing said guide sleeve toward said base, and means for limiting the reciprocable vertical travel of said plunger, a rotatable base holder head beneath said distributor, said base holder head comprising a body, a vertically reciprocable base elevating shaft and base holder assembly within said body, said base holder assembly comprising a base holder having a cup-like upper portion provided with resilient fingers and a flanged bottom portion, a retaining sleeve about said holder, a compressible rubber ring secured therebetween, and means for vertically reciprocating said shaft and rotating said head.
